GATE LATCH

George W. Schweitzer, Philadelphia, Pa.

Application April 20, 1950, Serial No. 157,012

6 Claims. (Cl. 292—150)

1

This invention relates to a locking rod for use on closure devices such as gates, doors, and the like, which rod is adapted to cooperate with a ring or surrounding keeper in a manner which will appear more fully hereinafter. The invention has been developed primarily as a safety device for use on folding gates of the pantographic type such as are employed at the head of stairs or other dangerous places where children must be protected against injury.

The primary object of the invention is to provide a device which will prevent a child from opening the gate while at the same time permitting ready actuation thereof by those in charge of the child or others authorized to pass the gate.

More specifically stated, the objects of my invention include the provision of a locking rod for the purpose described which is simple in design, inexpensive to manufacture and easily applied to the gate or other closure member upon which it is to be used. The invention also contemplates the provision of a locking rod which requires only the simplest cooperating keeper on the post or wall to which the gate is to be locked.

I have illustrated preferred embodiments of the invention in the accompanying drawing wherein:

Figure 1 is a side elevation of a pantographic type of gate to which my invention is particularly applicable;

Figure 2 is an enlarged vertical or longitudinal section through my improved locking rod showing the details of its construction and illustrating the manner in which it is secured to the gate illustrated in Figure 1, the parts being shown in the position they assume when the gate is unlocked;

Figure 3 is a section similar to Figure 2 but with the parts shown in locking position;

Figure 4 is a section on a still larger scale taken as indicated by the line 4—4 on Figure 3; and

Figure 5 is a fragmentary section similar to the sections of Figures 2 and 3 but illustrating a slight modification of one of the features of the invention.

As will be seen from the drawing, my improved locking rod includes a pair of elongated members which are relatively movable in a longitudinal direction. Preferably these take the form of an outer tubular member 6 and an inner pin-like or locking member proper 7, the diameter of the pin being substantially less than the inside diameter of the tube. Centering means in

2

the form of suitable washers 8 are secured to the pin and serve to guide the pin in its longitudinal movement within the tube 6. At the upper end the pin projects outwardly through a suitable opening in the tube and is bent around into the form of a handle-like loop 9 by means of which the locking rod can be actuated. The loop 9 has a reentrant portion 9a which is adapted to project through either one of two longitudinally spaced openings 10 and 11 located in the wall of the tube 6 near its upper end. The portion 9a is provided with an undercut 9b which is adapted to embrace the adjacent edge of either of the openings 10 and 11.

Between the upper washer 8 and a loose washer 12 in the upper end of the tube, I provide a resilient means in the form of a coil spring 13 which normally tends to move the members 6 and 7 to the position shown in Figure 3, the washer 12 being arranged to abut against the inwardly extending flange 12a at the top of the tube.

Toward its lower end the tube 6 is provided with a pair of opposed lateral openings 14 formed by cutting the opposite walls of the tube into tongue-like portions 15 which are subsequently bent inwardly to form upwardly facing wedging surfaces as clearly shown in Figures 2 and 3.

The lower end of the pin 7 is bifurcated to provide the opposed locking portions 16 which are adapted to be expanded or bent outwardly by the wedging surfaces 15 when the tube 6 and the pin 7 are moved relatively so as to force the wedging surfaces between the bifurcated portions 16. When this occurs the lower ends of the bifurcations 16 are deflected outwardly and project through the openings 14 where they will cooperate with the keeper 17. The parts should be arranged to cause the projection of the bifurcations 16 to take place at a point below the encircling keeper 17 so that the bifurcations will engage the undersurface of the keeper 17 and prevent withdrawal of the bolt from the keeper. This condition is shown in Figure 3. The keeper, it will be noted, can be of the simplest construction—the one I have illustrated being nothing more than an ordinary screw-eye which can be readily screwed into the wood of the adjacent post or wall 18 to which the gate is to be secured.

The gate 19 may be of the pantographic type having an inner end piece 20 which is permanently fastened to the post or wall 21 and an outer end piece 22 to which my improved locking rod is secured by means of a pair of straps 23.

In Figure 5 the wedging surface is made in a slightly different way. In this embodiment the metal of the tube 6 is cut out entirely to form the holes 14a and on the interior a solid wedge 15a may be secured by means of a transverse pin 24, the wedge 15a being located of course, so as to cooperate with the openings 14a and the bifurcations 16 of the pin in exactly the same way that the surfaces 15 cooperate with the corresponding parts in Figures 2 and 3.

From the description it is believed that the operation of the device will be fully apparent but it might be said that normally the parts are held by the spring 13 in the relative positions illustrated in Figure 3, in which position the gate is firmly secured to the keeper 17 in such a way as to prevent a child from opening the gate. However, an adult can easily grasp the handle 8, remove the end 9a from the opening 11 and by a slight pressure on the upper end of the tube 6 he can compress the spring 13 and then permit the end 9a to enter the upper opening 10 as shown in Figure 2. When this is done the bifurcations 16, of course, will be pulled upwardly away from the wedge surfaces 15. The bifurcations are made preferably of a suitable spring metal so that they will automatically approach each other as they are retracted. When they assume the position in Figure 2, it will be understood that the rod can be lifted upwardly until its lower end 30 clears the keeper 17, whereupon the gate can be moved to its open position.

I claim:

1. A locking rod adapted to cooperate with a surrounding keeper, said rod comprising a pair of elongated members which are relatively movable in a longitudinal direction, a locking portion on one of said members adapted to be expanded so as to engage the keeper and prevent withdrawal of the rod, and wedging means on the other member adapted to effect said expansion

upon relative movement of the members in one direction.

2. A locking rod in accordance with claim 1 having in addition resilient means normally urging said members to move in the direction which causes the expansion of said locking portion.

3. A locking rod adapted to cooperate with a surrounding keeper, said rod comprising an elongated tube, a locking pin slidable within said tube, a lateral opening in the tube, a wedge surface adjacent said opening, and a locking portion on the pin adapted to be deflected so as to project through said opening to engage the keeper and prevent withdrawal of the rod upon movement of the pin toward said wedge surface.

4. A locking rod in accordance with claim 3 having in addition resilient means normally urging the pin toward said wedge surface.

5. A locking rod in accordance with claim 3 wherein the wall of the tube is cut to form a tongue portion which is bent inwardly to provide the lateral opening and the wedge surface.

6. A locking rod in accordance with claim 3 wherein the wall of the tube is cut to form a tongue portion which is bent inwardly to provide the lateral opening and the wedge surface and wherein the end of the pin is bifurcated to provide the said locking portion.

GEORGE W. SCHWEITZER.
